UNITED STATES PATENT OFFICE.

DANIEL B. SEWARD, OF EASTHAMPTON, MASSACHUSETTS.

BUTTON.

SPECIFICATION forming part of Letters Patent No. 554,544, dated February 11, 1896.

Application filed December 1, 1894. Serial No. 530,568. (No model.)

To all whom it may concern:

Be it known that I, DANIEL B. SEWARD, of Easthampton, in the county of Hampshire and State of Massachusetts, have invented a 5 new and Improved Button, of which the following is a full, clear, and exact description.

Cloth-covered buttons—such as are ordinarily made for use on coats, vests, cloaks, and like garments—are open to the objection that 10 they can not be as securely and conveniently applied as could be desired, and also to the more serious objection that the ordinary tufts provided as a means of taking the thread cause the thread to be conspicuously exposed, 15 and the thread when faded lends a far from proper finish to the garment and is more liable to pull out than in the case of buttons having apertures.

The object of my invention is to provide a 20 combination-button in which a solid center of vegetable ivory, bone, or equivalent hard material is so formed as to afford proper support and engagement of the cloth covering, and a clamping ring or shell therefor, enabling 25 the button to be cheaply produced and the cloth covering to be neatly and securely applied.

The invention consists in the novel construction hereinafter particularly described 30 and defined in the claims.

Reference is to be had to the accompanying drawings, forming a part of this specification, in which similar letters of reference indicate corresponding parts in all the figures.

35 Figure 1 is a front view of a button embodying my invention, showing it applied. Fig. 2 is a central section at right angles to the plane of the button. Fig. 3 is an edge view of the solid center. Fig. 4 is a back view 40 of the button. Fig. 5 is a central sectional view illustrating a slight modification. Fig. 6 is a cross-section taken on the line 6 6, Fig. 7, illustrating a further modification; and Fig. 7 is a face view of the modification shown 45 in Fig. 6.

In forming a button in accordance with my invention an improved center A is provided and is formed of vegetable ivory, bone, or equivalent hard material, suitable apertures 50 a being provided therein for the securing-thread B. In order that the cloth covering C of the button may be secured conveniently

and properly, the solid center A is formed with a flange a' below the plane of the front a² of such center, thereby providing a projecting front end or neck a³ and a shoulder a⁴ outside of and at the base of the neck, the neck in practice preferably projecting slightly above the cloth covering to protect the same, as more clearly shown in Figs. 6 60 and 7 hereinafter referred to.

In connection with the cloth covering C and the solid center A a clamping ring or shell D is employed beneath the said covering, which ring or shell has a central opening of 65 sufficiently greater diameter than the neck or projecting part a³ to tightly receive the inner edge c of the covering between the inner edge of the ring D and the said neck, and such edge c of the cloth is turned under the 70 ring or shell and clamped against the shoulder a⁴ formed by the flange a', and is also snugly held against the neck or part a³. At the back of the button there is also formed on the solid center a neck or projecting central part a⁵, and against the back surface of the flange a' an apertured disk E is held, the neck a⁵ projecting through such disk. 75

The connection of the parts is completed 80 by effecting a clamped engagement of the disk E with the cloth C and clamping ring or shell D at the periphery of the button, the disk having an upwardly and outwardly flared outer edge e, over which fits the downwardly and inwardly curved outer edge d' of the ring 85 or shell D, as shown, the outer edge of the cloth covering following the bend of its said clamping ring or shell and being inturned and clamped between the edges e and d', as at c', as clearly appears in Fig. 2. With this 90 construction the cloth covering will be properly and securely held to the solid center A, the flange a' and neck a³ on the latter affording the proper engagement of the inner edge of the ring and cloth. 95

In the form shown in Fig. 5 the flange A' on the solid center A extends sufficiently therefrom to take the cloth and clamping ring or shell, as described, the button at the outer edge beyond the flange being filled with a ring 100 F of paper or other material, the button in all other respects being similar to the construction shown in Figs. 1 to 4.

In the form shown in Figs. 6 and 7 the cen-

ter A² is formed with a narrow flange a⁸, the neck a⁹ extending to such flange, which is at the periphery. Thus nearly the whole face of the solid center is exposed, the cloth covering C' extending only a short distance inward from the edge of the button. In this form, also, a filling-ring F, as well as a back-plate E, may be employed, as described above, and within or beneath the back-plate a cloth web G may overlie the back of the center A², covering the same. The center A² further has a surface or edge a¹⁰ projecting beyond the cloth covering C' to protect the latter.

Having thus described my invention, I claim as new and desire to secure by Letters Patent—

1. The button herein described consisting of the center of hard material provided on both sides at its middle with the projecting neck portions and having its outer edge or rim inclined inward from front to rear, a disk having an open center fitting snugly around the rear neck and bent inward surrounding said central opening effecting an edge contact with the rear side of the hard center, the said disk being bent at its upper edge along and against the outer beveled edge of the center, the cloth covering the outer side of said center, the clamping ring or shell arranged beneath the cloth, the inner edge whereof is in-turned around the inner edge of the central

opening in the clamping-shell, the outer edge of the clamping-ring being crimped together and against the outer rim portion of the rear disk, the center forming a solid bearing between the rear disk and front shell from the neck of the center to the outer edge of the button, all substantially as and for the purposes set forth. 35

2. A button substantially as described, consisting of a center comprising an inner section having necks and flange-like portion whose outer edge is formed cylindrical and the outer rim-like portion of paper or the like having its central opening cylindrical and fitted upon the cylindrical edge of the inner section and made slightly thicker than said cylindrical edge whereby to project beyond the face of the flange portion of the center, the cloth front and the clamping ring or shell 40 beneath the cloth, the inner edge of the cloth being inturned around the inner edge of the said ring and clamped thereby against the projecting edge of the outer rim-like portion of the center, and the rear disk, the outer edge of the shell and cloth being crimped together and against the outer edge of the disk, substantially as and for the purposes set forth. 45
